UNITED STATES PATENT OFFICE.

ABRAHAM LACKEY, OF RIALTO, CALIFORNIA.

SHIPPING OR PACKING BOX.

Application filed April 22, 1922. Serial No. 556,060.

To all whom it may concern:

Be it known that I, ABRAHAM LACKEY, a citizen of the United States, residing at Rialto, in the county of San Bernardino and State of California, have invented certain new and useful Improvements in Shipping or Packing Boxes, of which the following is a specification, reference being had to the accompanying drawings.

10 The purpose of the present invention is to provide a shipping or packing case or box, which is collapsible, in order that it may be disposed in a small compass, when not erected and in use, enabling the case or 15 box to be returned to the shipper or sender at a small expense.

Another purpose is the provision of a box or case, wherein the sides and ends are capable of resting upon the bottom, when 20 the parts are collapsed or knocked down, so that the cover may be connected to the bottom by means of strips, so as to hold the sides and ends in place, when the parts are in collapsed positions.

25 Still another purpose is to provide a shipping box or case, wherein the sides, ends, top and cover have interconnecting joints, to hold the parts in erected positions when the case is in use. The shipping box 30 or case is particularly adapted for shipping various produce, such as fruit, vegetables and the like. Also it is the aim to provide a shipping box or case, wherein the sides, ends, bottom, cover and intermediate pieces 35 or partitions may be perforated or not, preferably perforated for shipping various produce, thereby permitting circulation of air through the box.

It is to be understood that the particulars 40 herein given are in no way limitative and that while still keeping within the scope of the invention, any desired modifications of detail and desired proportions may be made in the apparatus according to circumstances.

45 The invention comprises further features and combination of parts, as will be hereinafter set forth, shown in the drawings and claimed.

In the drawings:—

50 Figure 1 is a view in perspective of the improved shipping case or box constructed in accordance with the invention, showing the box erected for use;

55 Figure 2 is a view in perspective showing the various parts of the shipping case or box collapsed;

Figure 3 is a horizontal longitudinal sectional view through the box or case;

Figure 4 is a vertical longitudinal sectional view on line 4—4 of Figure 1; 60

Figure 5 is a transverse sectional view on line 5—5 of Figure 1;

Figure 6 is a transverse sectional view on line 6—6 of Figure 2 transversely through the collapsed box or case; 65

Fig. 7 is a section showing in detail a joint between a side and end of the box.

Referring to the drawings, 1 designates the bottom of the box, 2 the sides thereof, 3 the ends, and 4 the cover. 70

The longitudinal edge portions of the bottom 1 are provided with inturned flanges 5 forming guides to be engaged by the lateral flanges 6 of the lower portions of the sides 2 of the box. The end edges of the 75 bottom have upstanding flanges 7, which act to prevent the sides from moving longitudinally.

The ends of the sides are bent upon themselves as at 8. The folded portions 9 caused 80 to be formed by so bending the ends of the sides lie flat against the inner faces of the sides. The folded parts 9 and the sides are bent at 10, so that the two parts 9 and portions of the sides between the bends 8 and 85 10 constitute flanges 11 extending at right angles to the sides, which prevent the end pieces 3 from moving outwardly. The inner portions of the folded parts 9 are rebent at 12 having flanges 13, which are parallel 90 to the sides, thereby forming channel guides 13^a, which receive the flanges of the end pieces 3, which may be inserted in position in a vertical direction, until the lower edges of the end pieces engage within the flanges 6 95 of the bottom. The flanges 11 prevent the side pieces from moving outwardly, while the flanges 11 prevent the end pieces from moving outwardly, when the cover is removed. 100

The upper longitudinal edges of the sides 2 terminate in beads 14 which have interior stiffening wires or rods 15. These beads act as guides for the cover 4, the longitudinal edges of which have overturned arcuate 105 guide channels 16 to receive the rolls, to hold the cover in position. One end edge of the cover 4 has a downturned flange 17, to engage one end of the shipping box or case, to limit the cover in its movement, when 110 connected to the sides of the box.

The bottom, side, ends, cover and an in-

termediate partition 18 may or may not be perforated, preferably perforated, so as to permit of a thorough circulation of air through the box, to keep the produce from 5 spoiling, as the box is particularly adapted for shipping perishable articles.

The sides 2 of the box have inturned struck-up lugs or tangs 19, which act as guides, for the reception of the flanges 20 of the trans- 10 verse partition 18, to hold the same in position.

Fastened to the bottom 1 in any suitable manner, preferably by rivets are transverse strips 21, which are located adjacent the ends 15 of the box. These strips have upturned ends 22, terminating in beads 23, which engage the downturned curved longitudinal flanges of the cover, when the box or shipping case is in a collapsed condition, as shown in Figure 2.

When the shipping box or case is not in use, the ends are disposed upon the bottom flatwise thereof, then the side pieces 2 are disposed upon the end pieces, the partition 25 having been arranged under the side pieces, after which the cover is connected to the up-standing ends of the transverse pieces 21 of the bottom, thereby holding the various parts in their collapsed positions, in order to permit the shipping case or box to be transmitted from one place to another in a small compass.

In order to collapse the shipping box or case, it is first necessary to remove the partition, by moving it vertically upwardly, that is to say after removing the cover. The end pieces are then moved vertically upwardly, after which the side pieces are free 35 to move inwardly, disengaging their lower flanges from the guides of the bottom.

The various parts of the shipping box or case may be constructed of any suitable material, preferably sheet metal, such as aluminum or the like, so that the box may be 40

made very light, thereby saving cost in shipping. 45

The invention having been set forth, what is claimed is:—

1. A shipping box comprising a bottom, 50 sides, ends and a cover adapted to have interlocking engagement with each other when the box is set up, the bottom having inturned guide flanges and the cover having beads, and members extending across the bottom and then extending upward and being 55 formed at the junction of the transversely extending portion with the upwardly extending portions with beads adapted to receive and interlock with the inwardly turned flanges, the upper ends of the upwardly extending portions being formed to engage in and interlock with the beads of the cover to thereby hold the parts in their knocked down condition.

2. A shipping box comprising a bottom, 60 sides, ends and a cover, the bottom being longer than the sides and wider than the ends and having its lateral margins upwardly and inwardly turned, the cover being longer than the sides and wider than the ends 70 and formed at its margins with inwardly extending open beads, and members applied to the bottom for holding the box in a knocked down condition, each member having a transverse portion disposed beneath 75 the bottom of the box and upwardly extending relatively short portions, each upwardly extending portion at its junction with the transverse portion being outwardly bowed to embrace the flange of the bottom and interlock therewith and the upper end of each upwardly extending portion being outwardly and then downwardly curved to fit in and interlock with the bead on the cover. 80

In testimony whereof I hereunto affix my signature.

ABRAHAM LACKEY.
